US00D893553S

(12) **United States Design Patent** (10) **Patent No.:** **US D893,553 S**
Vintzel (45) **Date of Patent:** **** Aug. 18, 2020**

(54) **AIR COMPRESSOR**

- (71) Applicant: **Harbor Freight Tools USA, Inc.**,
Calabasas, CA (US)
- (72) Inventor: **James Constantine Vintzel**, Jackson,
TN (US)
- (73) Assignee: **Harbor Freight Tools USA, INC.**,
Calabasas, CA (US)
- (**) Term: **15 Years**
- (21) Appl. No.: **29/733,744**
- (22) Filed: **May 6, 2020**

(57) **CLAIM**

The ornamental design for an air compressor, as shown and
described.

DESCRIPTION

FIG. 1 is a top-front perspective view of an air compressor
showing my design according to a first embodiment;
FIG. 2 is a front elevation view thereof;
FIG. 3 is a rear elevation thereof;
FIG. 4 is a right side elevation view thereof;
FIG. 5 is a left side elevation view thereof;
FIG. 6 is a top plan view thereof;
FIG. 7 is a bottom plan view thereof;
FIG. 8 is a bottom-rear perspective view thereof;
FIG. 9 is a top-front perspective view of an air compressor
showing my design according to a second embodiment;
FIG. 10 is a front elevation view thereof;
FIG. 11 is a rear elevation thereof;
FIG. 12 is a right side elevation view thereof;
FIG. 13 is a left side elevation view thereof;
FIG. 14 is a top plan view thereof;
FIG. 15 is a bottom plan view thereof; and,
FIG. 16 is a bottom-rear perspective view thereof.
The dashed broken lines in the figures illustrate portions of
the air compressor that form no part of the claimed design.
